(57) **CLAIM**

I claim, the ornamental design for a female receptacle of Y-buckle, as shown and described.

DESCRIPTION

FIG. 1 is a perspective view of a female receptacle of Y-buckle, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view thereof taken along line 'A—A' in FIG. 2; and,

FIG. 9 is a reference perspective view showing the female receptacle of Y-buckle coupled with a male latch of Y-buckle. The broken lines shown in FIG. 9 are for illustrative purposes only and form no part of the claimed design.
